Drawings from co-pending U.S. Appl. No. 29/563,098, filed May 2, 2016.

Primary Examiner — Catherine R Oliver-Garcia*(74) Attorney, Agent, or Firm* — Renner, Otto, Boisselle and Sklar, LLP(57) **CLAIM**

The ornamental design for a holster, as shown and described.

DESCRIPTION

FIG. 1 is a front, top, left perspective view of a holster showing my new design, a front, top, right perspective view being a mirror image thereof;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front, top, left perspective view of a second embodiment of a holster showing my new design, a front, top, right perspective view being a mirror image thereof;

FIG. 9 is a left side elevation view thereof;

FIG. 10 is a right side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The broken line showing is for the purpose of illustrating portions of the holster and forms no part of the claimed design.
